UNITED STATES PATENT OFFICE.

FREDERICK H. SCHULENBERG, OF LIMA, OHIO, ASSIGNOR TO THE VAPO STOVE COMPANY, OF LIMA, OHIO.

HYDROCARBON BURNER.

1,411,749.

Specification of Letters Patent.

Patented Apr. 4, 1922.

Application filed April 5, 1920, Serial No. 371,391. Renewed January 24, 1922. Serial No. 531,510.

To all whom it may concern:

Be it known that I, FREDERICK H. SCHULENBERG, a citizen of the United States, residing at Lima, in the county of Allen, State 5 of Ohio, have invented certain new and useful Improvements in Hydrocarbon Burners; and I do hereby declare the following to be a full, clear, and exact description of the invention, such as will enable others skilled 10 in the art to which it appertains to make and use the same.

This invention relates to hydrocarbon burners of that class in which the hydrocarbon is volatilized in an open trough and 15 has then added to the resultant gas, the atmospheric oxygen to effect its combustion.

In burners of this type with which I am familiar, the addition of atmosphere to the hydrocarbon gas, is effected in such manner and at such rate as to cool the gas or produce such a mixture, adverse either with 20 respect to its proportions or homogeneity as results in such incomplete combustion as is uneconomical and is further objectionable 25 by reasons of odors and carbon deposits.

It is the object of the present invention primarily to produce a burner in which the temperature of the gas of volatilization of the carbon, will continuously rise in temperature while having contributed to it successive charges of atmospheric oxygen, so that free carbon will not result and the maximum heat from the fuel will be obtained. This prime objective is accomplished by such form and arrangement of parts as ensures the rising of the gas through a zone of continually increasing temperature and further ensures successively higher temperatures to the charges of 30 air that are successively added to the rising gas. This particular arrangement not only provides against arresting the rising temperature of the gas but also ensures the addition of atmosphere at such temperature 35 and in such quantity at each point of admission, as results in a homogeneous mixture at that point. It will thus be clearly understood that if the gas gradually increases in temperature and there is added 40 to it successive charges of atmosphere at successive points of its zone of movement, then, if the added atmosphere has the proper temperature and is in proper quantity, there

will be so nearly complete combustion as will be without any appreciable evidence of 55 residue.

In the drawings:

Figure 1 is a vertical section taken centrally through that embodiment of the present invention that it has been elected to illustrate. 60

Figure 2 is a transverse section on line 2—2 of Figure 1.

Figure 3 is a transverse section on line 3—3 of Figure 1 through the cap and the 65 cupola of the head, with which the cap is engaged.

Figure 4 is a horizontal section on line 4—4 of Figure 1, through the air feeding head of the burner. 70

Figure 5 is a detail perspective view of the air feed head of the burner with its cupola, the air feeding cap being removed.

Figure 6 is a detail perspective view showing the ring that constitutes the base of the 75 air feeding head, and showing one of the stepped lugs that serves to hold the head in axial alinement with its base.

Figure 7 is a vertical section illustrating a modification of the air feeding head. 80

Referring now to the drawings, in the embodiment of the invention illustrated, there is shown a cylindrical base 10 having radiating flanges 11 through the medium of which it may be secured in operative position and from which base 10 there projects also a radial flange 12. The upper edge of the base 10 is rabbeted as shown at 13 to receive the lower edge of a frusto-conical casing 14 upon which is disposed a flat ring plate 15 having a depending annular flange 16 that fits within the casing 14 and holds the ring plate against lateral displacement. A second ring plate 17 is disposed above and in axial alinement with the ring plate 15, the casing 14 and the base 10 and has at its outer margin a plurality of depending lugs 18, the inner corners of which are notched as shown at 19 to receive corresponding portions of the periphery of the 90 ring plate 15, thus to hold the ring plate 17 in the said axial alinement. It will be noted that the mutually adjacent faces of the ring plates 15 and 17 are inwardly divergent, while the upper face of the ring plate 17 is 95 inclined slightly toward its axis. 100

The radial flange 12 of the base 10 has formed at its inner edge, an upwardly opening U-shaped, annular trough 20 and through the flange directly adjacent the 5 trough and at intervals of the flange, are formed inlet air openings 21 that permit air to rise into the air feed chamber between the trough 20 and the base 10.

The outer side of the trough 20 is higher 10 than the inner side, and both of them are parallel with the wall of the base 10. An oil feed pipe 22 provided with a control valve 23, extends through the base 10 and is screwed through a boss 24 on the outer wall 15 of the trough 20 and communicates with the trough.

The outer wall of the trough 20 is rabbeted at its upper edge as shown at 26, to receive a frusto-conical wall 27, the upper 20 minor end of which terminates slightly short of the ring plate 15 with the resultant air passage 28, while the interior diameter of this upper minor end of the frusto-conical wall 27 is the same as the inner diameter 25 of the ring 15. A succession of annular series of slots 29 are formed through the wall 27 and the material about each of the slots is pressed outwardly of the wall as illustrated, to provide outwardly directed lips 30 between which in practice, air passes to the combustion chamber A from the air feed chamber B as hereinafter particularly described.

The inner surface of the inner or lower 35 wall of the trough 20 is also rabbeted, as shown at 31 and receives the lower end of a second frusto-conical wall 32 that is spaced from the wall 27 and provides the combustion chamber A just referred to. The wall 0 32 has a longitudinal succession of annular series of slots 33', similar in all respects to the slots 29 having at their edges the lips 34 that correspond to the lips 30 but which, instead of being directed away from the 45 combustion chamber, are directed into it.

Upon the inner frusto-conical wall 32 is disposed a ring plate or disk 34^a having a central opening 44 and having notched lugs 35 depending from it at intervals of its 50 outer edge and in which notches 36 the top edge of the wall 32 is received. These lugs 35 hold the ring plate 34^a against lateral displacement from the wall 32 and also in spaced relation to its upper edge to provide 55 an annular succession of air passages 37 between the plate and wall.

The plate 34^a constitutes the bottom of a dome-shaped head 38, the bottom edge of which rests in the notches 39 of lugs 40 projecting upwardly from the plate 34^a adjacent its outer edge and which lugs serve not only to hold the dome and the plate 34^a against lateral displacement with respect to each other, but to hold them in spaced relation to provide an annular series of air pas-

sages 41, it being noted that the said air passages 41 are in a plane below the upper edge of the wall 27. Extending laterally through the wall of the dome 38 and in the plane of the ring plate 15, is a circumscribing series of perforations 42, which it will be noted communicate with the central opening 43 of the ring plate 15 and are directed toward the inner periphery of the ring plate. The dome continues tapering through 70 the central opening 45 of the upper ring plate 17, where it is provided with a cupola 46 communicating with it and which cupola in its side wall has a circumscribing series of slots 47 and in its top a central opening 51. 80 About the cupola and resting upon the dome which constitutes the air feeding head of the burner, there is disposed an air feeding cap comprising the vertically spaced plates 48 and 49 having the air chamber 50 between 85 them. The plates 48 and 49 are unconnected at their inner peripheries so that there is afforded free communication of the slots 47 with the chamber 50 while the plates adjacent their outer peripheries are connected 90 at intervals by the lugs 51' that hold them in fixed spaced relation.

A priming tube 53 leads through the outer wall of the trough 20 into the latter and when the burner is to be operated, the trough 95 is provided through this tube, with a charge of some suitable and comparatively highly volatile liquid fuel. The gas from this fuel rises in the chamber A and is ignited through the opening 45 of the ring plate 17 100 and the chamber A being filled with the flame, to which air is fed from the outer circumscribing chamber B and the inner air chamber C, which latter is defined by the wall 32. The flame within the combustion 105 chamber A serves to heat the trough 20 and all parts sustained thereby, this priming fuel being supplied in quantities sufficient to establish that temperature which will effect volatilization of kerosene or similar 110 heavy hydrocarbon that is subsequently admitted to the trough 20 through the pipe 22. Upon initial volatilization of the operating fuel, it of course ignites from the flame from the priming fluid. 115

It will of course be understood that the highest temperature of the burner is at its top, the temperature gradually decreasing to the trough. Thus, as the fuel gas rises through the chamber A, its temperature 120 gradually increases and it continues to increase in temperature as it passes through the entire burner. During this upward movement of the gas, air is fed to it through the slots 33, the air entering the gas in flat, 125 horizontal, thin sheets so as to effect an intimate mixture. As the metal of the wall 32 increases in temperature toward its upper end, the upward succession of air sheets increases in temperature so that the air sup- 130

plied to the gas rises in temperature as does the gas and it does not reduce the temperature of the gas. The projection of the lips 34 into the combustion chamber A causes 5 the adjacent portion of the column of rising gas to move comparatively slowly over the wall, thus to absorb a maximum of heat units. Additional air enters the combustion chamber A from the air feed chamber B, 10 through the slots 29 and the lips 30 serve to ensure such movement of the air over the outer surface of the wall 27 as effects a maximum absorption of heat units from the wall. Thus, the air, which is admitted from the 15 chamber B in thin horizontal sheets, is raised to such temperature as not to cool the gas, the upward succession of air sheets admitted, increasing in temperature from the increasing temperature of the wall, to correspond 20 to the increasing temperature of the gas.

As the gas moves past the upper edge of the wall 32, additional air is supplied by way of the opening 44, the interior of the 25 dome and the passages 41, then further air is supplied over the wall 27 through the air passage 28; then additional air is supplied through the perforations 42 from the dome; then further air is supplied from between 30 the ring plates 15 and 17, after which the gas strikes the bottom ring plate 49 of the cap and in its passage around the outer periphery of the cap, has further air supplied from the chamber 50 between the outer edges 35 of the ring plates 48 and 49. The cap deflects the flaming gas outwardly while some of the flaming gas curls inwardly over the cap and this latter portion is supplied with air through the opening 51 of the cupola 46. 40 With this succession of air charges, the air is added to the gas only at such intervals and in such quantity and with such temperature as will ensure its absorption by the gas without cooling of the gas and consequent 45 precipitation of carbon. The result is complete combustion with high economy of fuel.

Referring now to Figure 7 of the drawings, there is shown a modification of air feeding head that may be substituted for 50 the dome 38. This modified air feeding head consists of an inverted frusto-conical body 38' which is disposed on the lugs 40' of the bottom plate 34' corresponding to the plate 34^a in Figure 1. Through the wall 55 of the body 38' is formed a longitudinal succession of annular series of spaced slits 55 having the lips 56 directed outwardly of the wall above and below the slits so that the air that enters the head through the central opening 44' of the bottom plate 34', will be directed radiatingly from the head in thin horizontal sheets. The air feeding head 38' includes also a top plate 57 having depending lugs 58 at its outer edge portion 60 that are notched as shown at 59 to receive

the upper edge of the wall of the head and which hold the plate 57 in spaced relation to said upper edge to provide an annular series of air outlet passages 60. From the plate 57 there rises a cupola 61 having an annular series of slots 62 in its side wall that communicate with the cupola and therethrough with the head 38', the slots communicating also with the air chamber 63 between the plates 48' and 49' of the cap. These plates 48' and 49' are ring plates that receive the cupola in their central openings, the lower plate 49' resting upon the plate 57, the two plates being held in fixed spaced relation by the integral posts 64 that connect them at 70 intervals of their outer marginal portions.

Within the enclosure of the wall of the head 38' is a hollow inverted frusto-conical choking baffle 65, the opening in the lower minor end of which is in axial alinement 75 with the opening 44' and spaced upwardly therefrom. Through the wall of the baffle are formed perforations 66 and centrally from its solid top 67, there rises a stem 68 that is passed through a central opening 69 of 80 the cupola 61 and is held by a nut 70. Lugs 71 that depend from the plate 57, contact with the upper surface of the top plate 67 and hold the baffle against rocking movement. 85

In the use of the modified construction, it will be noted that it extends materially above the top ring plate 17 when positioned upon the wall 32 in place of the structure illustrated in Figure 1. The flame in its 90 passage to and through the central openings of the ring plates 15 and 17, has air supplied through the corresponding slits 55, which air has entered the head through the opening 44'. Further air is supplied through the 95 upper slits 55 to the gas above the plate 17 and also from the air chamber 63 between the outer edges of the ring plates 48' and 49' of the cap. 100

A part of the air that rises through the opening 44' passes directly to the wall of the head 38' and out through the slits 55, while the remainder rises into the baffle 65 where it is held sufficiently long to be superheated and then passes out through the perforations 66 and joins the first named quantity of air to raise its temperature to the desired point prior to its passage to the gas outside of the air feeding head. This baffle serves also to highly heat the air that passes 115 around it and over it to the cupola, whence it passes through the cap to join the gas at the outer edge of the latter. 120

In the actual and extended use of the invention, it is found that the combustion is 125 absolute, so far as any appreciable residue is concerned, so that toasting and broiling is permitted over the open flame. Furthermore, there is found to be a most economical use of fuel. As the separate parts are 130

removably assembled, the trough 20 may be exposed readily for removal of any residue that may accumulate.

It will be noted that the inner air chamber C is tapered upwardly so that the air when it expands as a result of the gradually increasing temperature as it rises in the chamber, must vent itself through the slits. The taper of this chamber and the number 10 and size of the slits is such that the air passes from the slits well across the combustion chamber, thus to effect an efficient mixture.

It will be noted also that the lips on the 15 inner wall of the combustion chamber, by projecting into the combustion chamber, will absorb heat from the burning gas and radiate it to the air sheets or streams that pass inwardly through the slits, thus insuring such temperatures to these air sheets or 20 streams, sufficiently high as to ensure against cooling of the gas, with the advantages previously referred to.

What is claimed is:

25 1. A hydrocarbon burner comprising an open topped fuel container, concentric horizontally continuous spaced walls disposed to receive between them gas of volatilization from fuel in the container, a head disposed 30 upon the inner wall and communicating with the interior thereof and having air passages directed outwardly over the wall, and plates above the outer wall spaced apart with a resultant air passage opening outwardly over the outer wall and inwardly 35 toward the head, and a cap supported upon the head and having an air passage therethrough communicating inwardly with the head and disposed to direct air outwardly 40 above said plates.

2. A hydrocarbon burner comprising an open topped fuel container, concentric horizontally continuous spaced walls disposed to receive between them gas of volatilization 45 from fuel in the container, a head disposed upon the inner air passages directed outwardly over the wall, and plates above the outer wall spaced apart with a resultant air passage opening outwardly over the 50 outer wall and inwardly toward the head, and a cap supported upon the head and having an air passage therethrough communicating inwardly with the head and disposed to direct air outwardly above said plates,

the head having a top orifice, opening above 55 the cap.

3. A hydrocarbon burner comprising an annular open topped fuel container, concentric frusto-conical perforated walls sustained upon and forming continuations of 60 the inner and outer walls of the fuel container, respectively, the inner wall having an enclosed air chamber, a plate disposed upon the inner wall in spaced relation to its upper edge with a resultant air passage 65 and having a central opening through it, a dome supported upon the plate in spaced relation to it with resultant air passages and having perforations through its wall above the plate, a cupola upon the dome having a central top opening and openings in 70 its side wall, a hollow cap encircling the cupola and communicating therewith through its wall openings, the cap having outer peripheral openings for passage of 75 air therefrom, and spaced ring plates supported upon the outer frusto-conical wall, the ring plates encircling and being spaced from the dome.

4. A hydrocarbon burner comprising an 80 annular open topped fuel container, concentric frusto-conical perforated walls sustained upon and forming continuations of the inner and outer walls of the fuel container, respectively, the inner wall having an 85 enclosed air chamber, a plate disposed upon the inner wall in spaced relation to its upper edge with a resultant air passage and having a central opening through it, a dome supported upon the plate in spaced relation 90 to it with resultant air passages and having perforations through its wall above the plate, a cupola upon the dome having a central top opening and openings in its side 95 wall, a hollow cap encircling the cupola and communicating therewith through its wall openings, the cap having outer peripheral openings for passage of air therefrom, and spaced ring plates supported upon the outer frusto-conical wall, the ring plates encircling and being spaced from the dome, the 100 perforations of the dome being in the plane of the lowermost ring plate and the cap being above the uppermost of the ring plates.

In testimony whereof, I affix my signature.

FREDERICK H. SCHULENBERG.
